UNITED STATES PATENT OFFICE.

WILLIAM M. DOUGLAS, OF GALVESTON, TEXAS.

GUN OR RIFLE.

1,141,383.

Specification of Letters Patent.

Patented June 1, 1915.

Application filed July 3, 1914. Serial No. 848,817.

To all whom it may concern:

Be it known that I, WILLIAM M. DOUGLAS, a citizen of the United States, residing at Galveston, in the county of Galveston and 5 State of Texas, have invented certain new and useful Improvements in Guns or Rifles, of which the following is a specification.

My invention relates to fire arms and more particularly to improvements in an automatic or semi-automatic gun or rifle.

An important object of the invention is to provide a gun or rifle, of the above mentioned character, so constructed that upon the discharge of the same, the empty cartridge 15 will be automatically withdrawn from the barrel, ejected from proximity thereto, and a new cartridge moved into the loading position to be shoved into the barrel, the final placing of the cartridge in the barrel 20 being effected automatically or manually.

A further object of the invention is to provide a gun or rifle of the above mentioned character, so constructed that the movable breech-bolt is stationary during the instant 25 of discharge, but a little after such discharge, as when the bullet leaves the muzzle, said breech-bolt is moved away from the rear end of the barrel, to remove the discharged cartridge and load the barrel with 30 a new cartridge.

A further object of the invention is to provide a gun or rifle of the above mentioned character, which is simple in construction, inexpensive to manufacture, strong, reliable 35 in operation, light, and convenient in use.

Other objects and advantages of the invention will be apparent during the course of the following description.

In the accompanying drawings forming a 40 part of this specification and in which like numerals are employed to designate like parts throughout the same, Figure 1 is a fragmentary side elevation of a gun or rifle embodying my invention, portions thereof 45 being shown in central longitudinal section, and interior portions in elevation, for the sake of illustration, Fig. 2 is a longitudinal sectional view taken on line 2-2 of Fig. 1, Fig. 3 is a transverse sectional view taken 50 one line 3-3 of Fig. 1, Fig. 4 is an end elevation of the reciprocating breech-bolt and housing therefor, Fig. 5 is a transverse sectional view through the breech-bolt and housing taken on line 5-5 of Fig. 2, Fig. 6 55 is a side elevation of the gun, showing the means to return the breech-bolt to the closed

position, Fig. 7 is an enlarged plan view of the breech-bolt returning means, parts being shown in section, Fig. 8 is an end view of the same, and, Fig. 9 is a side elevation of 60 the breech-bolt removed, partly in section.

In the drawings, wherein for the purpose of illustration is shown a preferred embodiment of the invention, the numeral 10 designates the stock of a gun or rifle, carrying 65 the usual fore-arm 11, as shown.

Rigidly secured to the fore-arm is a barrel 12, the inner end of which has screw-threaded engagement with a stationary breech-bolt housing 13. This breech-bolt 70 housing is rigidly secured to the stock and fore-arm by any suitable means.

Arranged within the breech-bolt housing 75 is an intermediate breech-bolt casing 14, held stationary therein by any suitable means.

Mounted to reciprocate within the breech-bolt casing 14 is a breech-bolt 15, to the upper side of which is rigidly secured a plate 16, having its opposite edges beveled, as shown in Fig. 5, to operate within grooves 80 17 formed in the breech-bolt casing 14.

The breech-bolt housing 13 and the breech-bolt casing 14 are provided upon their upper sides with longitudinally extending registering slots 17, receiving a lug 85 18, rigidly secured to the plate 16. The lug 18 is adapted to engage a stop 19, rigidly secured to the rear end of the breech-bolt housing 13, as shown.

As more clearly shown in Fig. 2, the 90 breech-bolt casing and housing are provided upon one side with openings 20, in registration, and affording a passage for the ejection of the cartridge shell 21. The breech-bolt 15 is preferably formed square in cross-section 95 whereby the same cannot turn within the breech-bolt casing 14.

As more clearly shown in Fig. 2, the forward portion of the breech-bolt 15 is provided upon one side with a longitudinally 100 extending recess 22, within which is arranged an extractor 23, attached thereto as shown at 24. This extractor is suitably resilient and is provided at its forward end with a hooked head 25 to detachably engage 105 with the flanged end of the cartridge 21 to effect a rearward longitudinal movement of the same. As more clearly shown in Figs. 1, 2, 5, and 9, the extractor 23 is provided with a longitudinally extending groove 26 110 to receive the forward end of a swinging ejector 27, pivoted within a chamber 28, as

shown at 29, with its forward end adapted to operate within the groove 22 and the groove 26. The pivoted ejector 27 has a laterally extending crank 30, adapted to enter the grooves 22 and 26, and when struck by the flange of the cartridge, to swing the ejector laterally, whereby the cartridge is thrown through the openings 20.

Arranged within the breech-bolt casing 13 is a plate 32, rigidly secured thereto by a screw 33 or the like. This plate has pivotal connection with a blade 35, adapted to enter a recess within the rear end of the barrel 12, and to automatically swing rearwardly or downwardly, when released, upon the rearward movement of the breech-bolt.

The function of this blade is to assist in guiding the cartridges from the magazine, to be described, to the rear end of the barrel. When the breech-bolt is drawn rearwardly and the blade 35 swung rearwardly or downwardly, cartridges may be fed into the magazine through the opening 17.

As more clearly shown in Fig. 1, the forward end of the breech-bolt 15 is formed solid and provided with an axial opening 37, to receive a reciprocatory firing pin 38.

Rigidly connected with the rear end of the firing pin is a head 39, carrying a vertically swinging holding-member 40, pivoted to the upper end thereof, as shown at 41. The firing pin extends through an opening in the holding-member 40, as shown. This holding-member has its lower end beveled, as shown at 43, for a purpose to be described. The beveled end 43 is adapted for detachable engagement with the upper beveled end of a holding-pawl 44 included in the trigger mechanism. This holding-pawl is pivoted at 46 to a vertically swinging lever 47. The lever 47 is pivoted at 48 and carries a depending trigger 49. This trigger carries a rearward extension 50 engaged by a leaf spring 51 tending to force the same downwardly.

The head 39 carried by the firing pin 38 is engaged by a compressible coil spring 53.

The numeral 54 designates a reciprocatory lock operating block or member, engaging the rear end of the spring 53. The rear end of the lock operating block 54 engages a coil spring 55, of greater strength and stiffness than the coil spring 53. At its rear end the coil spring 55 engages a block 56, closing the rear end of the breech-bolt and held therein by means of a transverse screw or element 57, also carrying a knob 58, as clearly shown in Fig. 2.

The lock operating block 54 carries a rearwardly extending horizontal arm 59, having its rear end in the form of a downwardly inclined depressing portion or tail 60. This downwardly inclined portion or tail 60 is arranged to slidably engage with the upper inclined or cam face of a pivoted lock-lever

61, secured to a casing 62, as shown at 63. This lock-lever operates within slots 64 in registration with each other and formed through the breech-bolt, breech-bolt casing and breech-bolt housing. The forward end 70 of the lock-lever engages a shoulder 65, thus positively preventing the rearward movement of the breech-bolt. The lock-lever 61 is provided upon its lower side with a recess 66 receiving the upper end or head 75 of a vertically reciprocatory pin 67. This pin is normally held in the upper position by a coil spring 68. When the trigger 49 is pulled the firing pin 38 moves forwardly exploding the cartridge. At the time of this explosion the lock-lever 61 holds the breech-bolt against rearward movement, but a little after the firing of the cartridge or about the time that the bullet leaves the forward end of the barrel, the spring 53 being expanded, the spring 55 expands, said spring 55 being stiffer than the spring 53, as above stated. The spring 55 now moves the lock operating block 54 forwardly, whereby depressing tail 60 swings the lock-lever 61 90 downwardly to release the breech-bolt. When this occurs, the pressure within the barrel moves the breech-bolt rearwardly, whereby the fired cartridge is ejected, by 95 the ejector 27.

In Figs. 6 to 8 inclusive, I have shown the automatic means to return the breech-bolt to its locked position, such means comprising a pair of telescoping tubes 69 and 70. The outer tube 69 is connected with the rear end of the breech-bolt by the screw or pin 57, the same operating through longitudinal slots 71. The forward end of the inner tube 70 is secured to the fore-arm by a saddle 72 or the like. A retractile coil spring 73 is arranged within the inner tube with its forward end secured to the inner tube and its rear end secured to the outer tube, by any suitable means. It is obvious that upon the explosion of the cartridge, the breech-bolt will be carried rearwardly, as above explained, placing the spring 73 under tension, which upon the reduction of pressure within the barrel, will move the outer tube 69 forwardly, automatically returning the breech-bolt to the forward closed position. I have found that satisfactory results are obtainable by dispensing with the automatic means to return the breech-bolt to the forward closed position, the same being returned to the closed position by hand with the use of the knob 58. Arranged below the forward portion of the breech-bolt housing and breech-bolt casing, 11 is a magazine casing 74, having communication with the rear end of the barrel. This magazine casing contains the new cartridges 21 to successively supply a cartridge to the barrel when the breech-bolt moves rearwardly by and upon the discharge of pre-

vious cartridges. The cartridges are automatically fed upwardly within the magazine casing, by a spring 75, the upper portion of which is secured to a feeding member 76, as shown.

The operation of the gun is as follows:— Assuming that the same is loaded, and cocked, the parts assuming the position shown in Fig. 1, upon pulling the trigger 49, pawl 44 releases the holding element 40, allowing the spring 53 to drive the firing pin 38 forwardly. The lock-lever 61 now holds the breech-bolt against rearward movement, upon the firing of the cartridge. The spring 53 expands upon the forward movement of the firing pin, whereby after or about the time that the bullet leaves the forward end of the gun, the spring 55 expands, carrying the lock operating block 54 forwardly, whereby element 59 depresses the lock-lever 61 to release the breech-bolt. The breech-bolt now automatically moves rearwardly to the open position, the springs 53 and 56 being again placed under tension and the holding element 40 engaged by pawl 44, whereby the firing pin is cocked. Upon this rearward movement of the breech-bolt the extractor 23 carries the exploded cartridge rearwardly with it whereby the same is moved into proximity to the ejector 27, which is engaged by the rim of the cartridge, and suddenly swung laterally, throwing the exploded cartridge out through the openings 20. By this time the pressure within the barrel is reduced sufficiently whereby the spring 73 automatically returns the breech-bolt to the forward closed position, the new cartridge being advanced forwardly of the breech-bolt, and carried into the rear end of the barrel by such forward movement.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:—

1. In a gun or rifle, a barrel having its rear end provided with a breech-bolt casing, a reciprocatory breech-bolt having slidable engagement with the breech-bolt casing, a firing pin carried by the breech-bolt and movable longitudinally thereof, a lock to normally hold the breech-bolt against rearward movement, a lock operating member carried by the breech-bolt to move longitudinally with relation thereto, spring means to effect the forward longitudinal movement

of the firing pin and subsequently the forward longitudinal movement of the lock operating member to release the breech-bolt 65 after the firing pin has reached the end of its forward travel, and trigger means adapted to hold and release the firing pin with respect to forward movement.

2. In a gun or rifle, a barrel having its rear end provided with a breech-bolt casing, a reciprocatory breech-bolt having slidable engagement therewith, a pivoted lock element adapted to engage and disengage the breech-bolt, means to normally hold the pivoted lock element in a position to engage with the breech-bolt, a member carried by the breech-bolt and movable longitudinally thereof and carrying a device to slidably engage with the pivoted lock element to move 80 the same out of engagement with the breech-bolt upon the forward movement of the member, a spring to move the member forwardly when free to move in that direction, and cartridge firing means carried by the 85 breech-bolt and controlling the forward movement of the member.

3. In a gun or rifle, a barrel having its rear end provided with a breech-bolt casing, a reciprocatory breech-bolt having slidable 90 engagement therewith, a firing pin carried by the breech-bolt, a spring to move the firing pin forwardly when released, a lock to normally hold the breech-bolt against rearward movement, a lock operating member 95 carried by the breech-bolt to move longitudinally thereof and having engagement with the spring, and a second spring engaging the lock operating member, substantially as described.

4. In a gun or rifle, a barrel having its rear end provided with a breech-bolt casing, a reciprocatory breech-bolt having slidable engagement therewith, a firing pin carried by the breech-bolt, a spring to move the firing pin forwardly when released, a pivoted lock lever normally engaging the breech-bolt to hold it against rearward movement, a lock operating member carried by the breech-bolt to move longitudinally thereof and provided with a downwardly inclined depression tail to slidably engage the lock lever and having its forward end engaging the spring, a spring having greater strength than the first named spring and engaging the rear end of 115 the lock operating member, and trigger means to temporarily hold the firing pin against movement.

In testimony whereof I affix my signature in presence of two witnesses.

WILLIAM M. DOUGLAS.
